UNITED STATES PATENT OFFICE

ERNST SIMON, OF BERLIN, GERMANY

WOODEN TIE OR SLEEPER FOR RAILROADS AND SIMILAR PURPOSES

Application filed March 24, 1931, Serial No. 524,953, and in Germany April 3, 1930.

This invention has reference to wooden ties or sleepers for railroad and similar purposes, and it is intended to devise means of increasing the life and the durability of such ties and particularly of ties made from relatively soft wood. It is a well known fact that by the thrusts and other strains occurring in the operation of the railroad the ties are subjected to varying compressing stresses by blows, jars or the like against the surface of the ties which is acted upon by the pressure of the rail or of its supporting plates. As a result of these stresses occurring in the operation of the rails the material of the ties is compressed and in the course of time the surface of the ties will become gradually worn out. In order to overcome these difficulties it has already been suggested to arrange insertion pieces made from a material of greater pressure resisting properties than the material of the ties themselves at those points of the surface of the ties which are exposed to the pressure of the rail or of the washer or supporting plate. Such insertion pieces, as heretofore suggested, were made to extend on the entire supporting surface in contact with the rail or with the washer or supporting plate, so that these inserts were intended to act as supporting means from the start.

Now in accordance with this invention the insertion piece is arranged in or on the tie in such a manner that its surface is situated somewhat below the pressure surface and by this means the outer surface of the tie itself constitutes the supporting means originally, while only after a certain compression of this softer material, the inserts which consist of material of greater hardness are also called upon to support the load. In view of the fact that the destruction of the fibers of the ties takes place only, as soon as the compression of the material exceeds the limit of elasticity of the wood of which the tie is composed, that is to say, that the mechanical destruction is not effected, before this point is reached, the inserts which counteract the overstepping of the limit of elasticity constitute an important means of increasing the life of the wooden ties or sleepers. As a result of the use of these inserts

the rails or their washers or supporting plates are caused from the start and permanently to rest uniformly upon the tie, and a better distribution of the compressing strains and a sufficient amount of elasticity are secured. 55

On the accompanying drawing the invention is shown in perspective view as embodied in an ordinary wooden tie.

Into the tie *a* which is composed of soft-wood insertion pieces *b* of dove-tailed cross-section and composed of hard wood are inserted by means of correspondingly shaped notches. The outer surface *b*₁ of the insert of hard wood recedes somewhat with relation to the surface *a*₁ of the tie *a* itself, so that the insert *b* of hard wood is only called upon to support the weight, after a certain amount of compression of the surface of the tie has occurred by the load due to the operation of the railroad. Obviously, the inserts may also assume any other suitable shape and arrangement. 65 70

The invention, of course, is not restricted to any particular configuration and kind of material and may be modified in accordance with varying conditions of application, except as otherwise stated in the appended claims. 75

I claim:—

1. In a wooden railroad tie insertion pieces of harder material than the tie and inserted in the supporting surface thereof somewhat below the level of said surface. 80

2. Wooden railroad tie, comprising in combination, a body part of comparatively soft wood, a plurality of notches in the supporting surface of the tie and inserts of comparatively hard wood in said notches, the upper surfaces of said inserts being somewhat below the level of the tie. 85 90

3. Wooden railroad tie, comprising in combination, a body part of comparatively soft wood, substantially dove-tailed transversely extending notches in the supporting surface of the tie and insertion pieces of comparatively hard wood in said notches and of some-what lower height than said notches. 95

In testimony whereof I affix my signature.

ERNST SIMON. 100
